UNITED STATES PATENT OFFICE.

ALBERT T. OGDEN, OF POUGHKEEPSIE, NEW YORK.

DESIGN FOR A MEMBER FOR MATCH-SAFES.

SPECIFICATION forming part of Design No. 37,327, dated February 7, 1905.

Application filed November 26, 1904. Serial No. 234,403. Term of patent 3½ years.

To all whom it may concern:

Be it known that I, ALBERT T. OGDEN, a citizen of the United States, residing at Poughkeepsie, in the county of Dutchess and State of New York, have invented a new, original, and ornamental Design for a Member for a Match-Safe, of which the following is a specification, reference being had to the accompanying drawing, forming part thereof.

5 The figure is a front perspective of the member of the match-safe, showing my design.

What I claim as new, and desire to secure by Letters Patent, is—

The ornamental design for a member of a match-safe, as shown.

ALBERT T. OGDEN.
